E. C. STAFFORD

TRAIN SIGNAL SYSTEM

Filed March 25, 1921

UNITED STATES PATENT OFFICE.

EARL C. STAFFORD, OF PHILADELPHIA, PENNSYLVANIA, ASSIGNOR TO THE UNITED STATES TRAIN SIGNAL COMPANY, OF PORTLAND, MAINE, A CORPORATION OF MAINE.

TRAIN-SIGNAL SYSTEM.

Application filed March 25, 1921. Serial No. 455,634.

My said invention relates to an improved interlocking train signal system intended particularly for use in railway trains. The attachment which comprises the main feature of improvement in my device may be used to advantage in connection with the signaling device shown in the application of Benn and Davies No. 380,286, filed May 10, 1920 and is so shown in the drawings. It is an object of my invention to provide simple and inexpensive means whereby a signal may be transmitted from any car equipped with electro-pneumatic signaling devices of the general type shown in said application to the engine, whether or not all the train units are so equipped.

Referring to the accompanying drawings which are made a part hereof and on which similar reference characters indicate similar parts,

Figure 1 is an elevation of a part of a train of cars with an engine showing my device in use,

Figure 2 is a similar view on a larger scale showing my attachment as applied to an electro-pneumatic signal.

Figure 3 is a section of my attachment, Figure 4 is a detail,

Figure 5 is an enlarged detailed view of the signal controller,

Figure 6 is an enlarged detailed view of the valve of Figure 2.

In the drawings reference character 10 indicates a signaling device of the general character specifically disclosed in my prior application No. 380,151, filed May 10, 1920.

Said signal device comprises a signal arm 50 mounted on an arbor 51 having a crank arm 52 thereon which is connected by means of a connecting rod 53 with a pivotally mounted lever 54 supporting the core 55 of an armature 56 carried by the electromagnet 57. A valve 58 closes a passage 59 when said valve is maintained in elevated position by means of the core 55 when the electromagnet is energized thus preventing the passage of air from the pipe 11 to and through the pipe 15.

This signaling device is connected by means of a conduit 11 to the air brake train pipe 12 and may be identical with the device of the prior application, except that the aperture 13 of the "sisser" 14 is in this case smaller than the ports in the device inter-

mediate the "sisser" and the pipe 11 leading to the air brake train pipe. In this way air brake train pipe pressure is built up in the device 10 all the way to aperture 13. I may leave the fixture 10 as in my prior application, merely adding the new attachment above or below the lateral pipe carrying the whistle or sisser 14. Preferably, however, I substitute therefor a bent pipe 15 leading down to a central chamber in the body 16 of the attachment. Pipe 15 is connected by screw threads to a plug 17 threaded in one end of body 16 and a passage 15' leads through the plug to the central chamber. A beveled ridge 18 surrounds this passage and has transverse grooves 19 communicating with the chamber.

A piston 20 in the chamber is loosely connected to a rod 21 having a collar 22 forming a valve to rest on a seat at 23. The piston is normally held as shown in Figure 3 so as to close the passage 15' and also to close a lateral passage 24, by means of a spring 25, which also holds the valve 22 on its seat 23 to close port 26 leading from the signal pipe to the outer air.

Spring 25 rests at one end in a pocket of a plug 27, having threaded engagement with body 16, and a pipe 28 threaded in the plug connects the device to another pipe 29 which leads from the train air signal pipe 30. A valve 31 is located in the connections and preferably as shown in Figure 2.

I have shown in Figure 1 part of a train comprising a car 32 equipped with an electro-pneumatic signal device as described in this application, the engine also having a signal 10 thereon. Cords 33 operate the air signals of ordinary type now in use in the conventional manner, both on the equipped car and on unequipped cars 34 and 35.

The signals are in circuit with conductors 36 and 37 and these conductors extend through hose connections 38 of the train air signal pipes as in application No. 380,286. The conductor's cord 39 operates circuit breaker 40 shown in Fig. 5, the same as in that application.

The device of Figure 3, when air is admitted from the air-brake pipe through pipe 11 will operate by the pressure of the air to depress the piston until passage 24 is uncovered after which the piston may still move but more slowly. As the piston is

moved the valve 22 is forced off its seat and the passage 26 is opened to relieve the pressure in the train air signal pipe, thus producing a signal on the train in the usual manner. Let it be assumed that certain units of the train are equipped with our electro-pneumatic signaling device, as for example, the engine and the second car from the engine as shown at Figure 1. If the 5 units intermediate the equipped units are supplied with the ordinary train air signal pipe found on all passenger, baggage and express cars the conventional signal 60 may be made to operate regardless of whether or 10 intermediate cars have the electro-pneumatic signaling device.

The train should preferably be made up so as to place all equipped cars at the rear, with unequipped cars, if there are any, between the foremost equipped car and the engine. Valves 31 are then turned off on all cars 15 except the one nearest the engine to prevent waste of air and undue lowering of pressure in the signal pipes. The valve 31 on the engine is also turned off, as the electro-magnet of the signal is not energized under these conditions. The switch at the front end of the foremost equipped car, as in application No. 380,286, is closed to close the circuit 20 through all the equipped cars, a switch at the rear of the last car being also closed. The signaling system is now ready for operation. A pull on the conductor's cord 39 will break the circuit at 40 on the equipped 25 car, hence will deenergize the electro-magnets on that and all connected equipped units thus causing the operation of a signal on each equipped car and also operating the ordinary signal now in use on the engine 30 in the usual way through passage 26 and thus operating the signal of hitherto known type on the engine. Because of the slowness of travel of the air in the train air signal pipe and for other reasons it is somewhat impracticable to operate trains of 35 length greater than eight cars, the signaling system in trains of greater length being more or less inefficient and unreliable. With my device on the other hand any 40 number of equipped cars may be added to the rear of a train and because of the electrical feature the release of pressure will always occur on the foremost equipped car. If therefore even as many as 8 or 10 unequipped 45 cars intervene between such foremost car and the engine the ordinary signal pipe on said cars will still cause the operation of the engine air signal with maximum efficiency.

60 The use of my device in the situation described does not interfere at all with the operation of the ordinary air signal pipe which may be used as before and will be so used on unequipped cars. In a situation such as that shown in Figure 1, where

unequipped cars happen to be located behind the foremost equipped car, the ordinary air signal must of course be used on such unequipped cars, it being operated exactly as heretofore, a pull on a cord 33 giving a signal to the engineer. It is to be noted that in the use of my device on a train such as first described the air may be cut off at the rear of the combination car, i. e., the foremost equipped car, whereby the expense of keeping up air pressure in the rear cars of the train is done away with. This device as above stated is intended for use during a transition period where some cars will be equipped and some will not be equipped with the electro-pneumatic signaling device. Should a train be made up entirely of cars equipped with the device of this application all of the valves 31 may be closed and the system will then operate as if they were absent similarly to my application No. 450,195, filed March 7, 1921. No air pressure is then needed in the signal pipe, which serves merely as a conduit for the wires of the train pipe signal.

While I have illustrated and described a preferred form of my invention I do not limit myself thereto, as numerous modifications will occur to those skilled in the art. For instance, under some conditions I might arrange the signal pipe to operate with "straight" air pressure, the pressure in the signal pipe being augmented on operation of a cord 39, instead of decreasing. The true scope of the invention is shown by the appended claims.

Having thus fully described my said invention, what I claim as new and desire to secure by Letters Patent, is:

1. In a train signaling system a plurality of train units, an air-brake pipe therefor, one or more of said units being equipped with electro-pneumatic signaling means and others of said units not being so equipped, said signaling means comprising a signal and means connected to the air-brake pipe for operating the signal, connections between the signaling means and the air signal pipe for giving a signal to the engineer on operation of such signaling means and means in each of said connections for disabling the same whereby the action of the air signal system may be eliminated if all cars are equipped with electro-pneumatic signaling means, substantially as set forth.

2. In a train signaling system for trains embodying an air brake pipe, an air signal pipe, and an air operated signal on the engine, the combination therewith of an electro-pneumatic signal on the engine, electro-pneumatic signals on one or more cars and means including connections between the air brake pipe, the air signal pipe and the electro-pneumatic signal on the cars for operating the air signal on the engine when-

ever any of said electro-pneumatic signals on the cars are operated, substantially as set forth.

3. A train signaling system comprising a pneumatically operated signal on the engine, an air signal pipe extending through the train, means on individual cars of the train for producing a variation of pressure in the air signal pipe to cause operation of said signal, means including a normally closed electric circuit on one or more of said cars controlling said signal-operating means, and means for breaking the circuit, substantially as set forth.

15 4. A train signaling system comprising a pneumatically operated signal on a car, a connection to a source of air under pressure for operating the signal, means including a normally closed electric circuit to prevent 20 operation of the signal, a connection from the train signal pipe to the atmosphere, a valve in said connection normally closing the same, and pneumatic means for opening the valve concurrently with the operation 25 of said signal, substantially as set forth.

5. In a train signal system, an air brake pipe, a train signal pipe, a signal for attachment to a train unit, a signal on the engine, means for operating said first-named signal 30 embodying a pipe connecting the signal to

the air brake pipe, a valve in said connecting pipe, means for controlling said valve including an electric circuit, a pipe leading from said connecting pipe to the train air signal pipe, and a valve therein controlled by pressure from the air brake pipe and arranged to be opened by the flow of air through the connecting pipe when the valve in said pipe is operated to permit such flow of air and adapted when opened to lower the pressure in the signal pipe for operating the signal on the engine, substantially as set forth.

6. In a train signaling system, a plurality of train units, an air brake pipe therefor, one or more of said units being equipped with electro-pneumatic signaling means and others of said units not being so equipped, said signaling means comprising a signal and means connected to the air brake pipe 45 for operating the signal, and connections between the signaling means and the air signal pipe for giving a signal to the engineer on operation of such signaling means, substantially as set forth.

In witness whereof, I have hereunto set my hand and seal at Washington, District of Columbia this 16th day of March, A. D. nineteen hundred and twenty-one.

EARL C. STAFFORD. [L. S.]
